UNITED STATES PATENT OFFICE.

HENRY JOSEPH ROUND, OF LONDON, ENGLAND, ASSIGNOR TO RADIO CORPORATION OF AMERICA, OF NEW YORK, N. Y., A CORPORATION OF DELAWARE.

THERMIONIC DEVICE FOR WIRELESS TELEGRAPHY AND TELEPHONY.

Application filed August 26, 1920. Serial No. 406,181.

To all whom it may concern:

Be it known that I, HENRY JOSEPH ROUND, a subject of the King of Great Britain, and resident of 9 Woodberry Crescent, Muswell 5 Hill, London, England, have invented new and useful Improvements in Thermionic Devices for Wireless Telegraphy and Telephony (for which I have filed an application in England dated August 7, 1919), of 10 which the following is a specification.

This invention relates to improvements in thermionic devices for wireless telegraphy and telephony and has for its object the production of a valve having a low resistance.

15 It is well known that in thermionic devices of the Fleming valve type the space current flowing (i) is equal to KV^n where V represents the anode volts applied and K is a function of the mechanical dimensions 20 of the valve. With a cylindrical anode and an axial filament K varies directly as the length (l) of the cylinder and inversely as its radius or

$$i = \frac{kV^n l}{x} \quad (1)$$

25 where x is the radius or distance between the anode and cathode. If the anode and cathode are parallel surfaces K varies directly as the area of the surfaces and inversely as the square of the distance between them or

$$i = \frac{kV^n r l}{x^2} \quad (2)$$

35 where x is the distance between the anode and cathode, l the length and r the radius of the cathode. To obtain a valve having low resistance therefore it is necessary in the 40 case of cylindrical anodes to make the length of the cylinder large and its radius small, an arrangement which usually introduces mechanical troubles.

According to this invention and to obviate 45 the difficulty, I provide a valve having an anode in the form of a grid-like structure of large area arranged at a comparatively great distance from the filament, while around this anode and as near to it as possible I arrange a second anode. I then make 50 the first anode positive by applying to it sufficient voltage to bring up to it enough electrons for the required purpose, and I treat this first anode as though it were itself the 55 actual source of the electrons and the poten-

tial were applied between it and the second anode.

A third electrode or control member preferably also of grid form can be introduced in order to give electric control and to furnish a low resistance valve having high magnifying properties.

My invention is illustrated by the accompanying diagrams, in which;

Fig. 1 is a diagrammatic view illustrating the invention.

Fig. 2 is a section through a valve constructed according to my invention.

Fig. 3 shows another form in which the two grids and the anode are flat.

Fig. 4 shows another form of valve.

Fig. 5 is a section on the line A—A of Fig. 4.

Fig. 6 is a detail view of the supporting member used in the form shown in Fig. 4.

Fig. 7 is a diagram showing an arrangement of circuits utilizing a valve.

In Figure 1, G and A represent respectively a grid-like anode and anode at distances r and $r+x$ from a filament F , x being the distance between G and A . Then if sufficient voltage is applied between G and F , G being made positive, G can be considered as a new source of electrons, and the current between G and A as given in (2) will be $krV^n l/x^2$, whereas if A had been a cylinder at distance x from the filament the current as given in (1) would have been $kV^n l/x$. Therefore for the same value of V the ratio of these currents is r/x , that is to say, by making r large and x small the resistance of the valve is reduced.

Now the distance of a cylinder from a filament must usually be larger than is desirable because of the difficulty introduced by the expansion of the filament, whereas two cold electrodes can be mechanically anchored very near together, so that the distance x may be made very small.

In Figure 2, F is a straight stretched filament, G is a prismatic grid-like anode stretched upon four supports S of steatite, glass, metal or other suitable material, and A is an anode surrounding the whole. Between the grid like anode and the outer anode is a control grid g stretched on supports s which are of steatite or other insulating material.

In Fig. 3 the grid like anode G and the grid g and the anode A are in the form of

flat plates separated by flat insulating members s , S .

In the form of valves shown in Figs. 4, 5 and 6 the grid like anode G is formed of a number of turns of wire wrapped round two opposite faces S of a steatite former having the general shape of a parallelepiped. The other faces s , s , are wider than the faces S and the grid g is formed of a number of turns of wire wrapped round these faces s so that the wires constituting the grid like anode G are separated by a small distance on both sides from the wires constituting the grid g . In the middle of the grids is a filament F supported by leading-in wires f at one corner of the former and by a wire f' at the opposite corner. The anode consists of two square plates Λ , one at each side, supported from pins a on the former.

Figure 5 is a diagram showing the arrangement of the circuits, when such a valve is to be used for amplifying. The incoming oscillations are led into the oscillatory circuit O connected to the grid g and the filament. B is a battery by which the grid like anode G can be made positive. The anode-filament circuit contains a battery b and an oscillatory circuit o the currents in which can be caused to influence a detector in any ordinary way.

What I claim is:—

1. In a thermionic device the combination of a cathode, an anode situated at a distance from the said cathode, a second anode situated on that side of the first anode which is remote from the cathode, the distance between the first anode and the second anode being small as compared with the distance between the first anode and the cathode and means for applying a positive potential to the first anode.

2. In a thermionic device the combination of a cathode, an anode situated at a distance from said cathode, a second anode situated on that side of the first anode which is remote from the cathode, the distance between the first anode and the second anode being small as compared with the distance between the first anode and the cathode, a control grid situated between the first anode and the second anode and means for applying a positive potential to the first anode.

3. In a thermionic device the combination of a cathode, an anode surrounding said cathode, a second anode surrounding the first anode, the distance between the first anode and the second anode being small as compared with the distance between the first anode and the cathode and means for applying a positive potential to the first anode.

4. In a thermionic device the combination of a cathode, an anode surrounding said cathode, a second anode surrounding the first anode, the distance between the first anode and the second anode being small as

compared with the distance between the first anode and the cathode, a control grid situated between the first anode and the second anode and means for applying a positive potential to the first anode.

5. In a thermionic device the combination of a heated filamentary cathode, a cold anode situated at a distance from the heated cathode, a second anode situated on that side of the cold anode which is remote from the heated cathode, the distance between the cold anode and the second anode being small as compared with the distance between the cold anode and the heated cathode, means for applying a positive potential to the cold anode, and means for applying a greater positive potential to the second anode.

6. In a thermionic device a combination of heated filamentary cathode, a cold anode situated at a distance from the heated cathode, a second anode situated on that side of the cold anode which is remote from the heated cathode, the distance between the cold anode and the second anode being small compared with the distance between the cold anode and the heated cathode, a control grid situated between the cold anode and the second anode, means for applying a positive potential to the cold anode, and means for applying a greater positive potential to the second anode.

7. In a thermionic device the combination of a heated cathode, a grid-like anode spaced from the heated cathode, a second anode adjacent the grid-like anode, the distance between the grid-like anode and the second anode being small compared with the distance between the grid-like anode and the heated cathode and means for applying positive potential to the grid-like anode.

8. In a thermionic device the combination of a heated cathode, a grid-like anode spaced from the heated cathode, a second anode adjacent the grid-like anode, the distance between the grid-like anode and the second anode being small compared with the distance between the grid-like anode and the heated cathode, a control grid situated between the grid-like anode and the second anode and means for applying a positive potential to the grid-like anode.

9. In radio receiving apparatus the combination with a thermionic device having a heated filamentary cathode, a cold anode situated at a distance from the heated cathode, a second anode situated on that side of the cold anode which is remote from the heated cathode, the distance between the cold anode and the second anode being small compared with the distance between the cold anode and the heated cathode and a control grid situated between the cold anode and the second anode of means for applying a positive potential to the cold anode and means for applying a signalling potential.

between the heated filamentary cathode and the control grid.

10. In radio receiving apparatus the combination with a thermionic device having a heated cathode, a grid-like anode spaced from the heated cathode, a second anode adjacent to the grid-like anode, the distance between the grid-like anode and the second anode being small compared with the distance between the grid-like anode and the

heated cathode and a control grid situated between the grid-like anode and the second anode of means for applying a positive potential to the grid-like anode and means for applying a signalling potential between the 15 heated cathode and the control grid.

In testimony that I claim the foregoing as my invention I have signed my name this 29th day of July A. D. 1920.

HENRY JOSEPH ROUND.
